(57) **CLAIM**

The ornamental design for an antenna structure, as shown and described.

DESCRIPTION

FIG. 1 is a perspective view of an antenna structure showing our new design;

FIG. 2 is a top plan view thereof, the bottom plan view being a mirror image thereof;

FIG. 3 is an enlarged view of a portion of the antenna structure shown in FIG. 4;

FIG. 4 is a front elevation view thereof;

FIG. 5 is a rear elevation view thereof;

FIG. 6 is a left side elevation view thereof; and,

FIG. 7 is a right side elevation view thereof.
